UNITED STATES PATENT OFFICE.

FRANCIS LEE CASTLEMAN, OF PENCOYD, PENNSYLVANIA.

COLUMN CONSTRUCTION.

Application filed January 19, 1923. Serial No. 613,655.

To all whom it may concern:

Be it known that I, FRANCIS LEE CASTLEMAN, a citizen of the United States, and resident of Pencoyd, in the county of Montgomery and State of Pennsylvania, have invented certain new and useful Improvements in Column Constructions, of which the following is a specification.

My invention relates to building columns and particularly to compound columns for use in constructing the framework of high buildings and similar structures, and has for its object the provision of a compound column, H-shaped in cross section, wherein the outer faces of the column in a direction parallel to its web are equidistant from each other throughout the length of the compound column, or throughout a portion of the length of the compound column through a number of successive stories. It also has for its object the provision of a compound H-shaped column wherein the overall dimension face to face of the column sections is made constant in adjacent, similar columns of varying cross sectional areas.

In high buildings employing compound columns the cross sectional area decreases from the bottom section upward, because the load on the column also decreases from the bottom towards the top thereof. Heretofore, it has been the practice to vary the overall dimension, face to face of the cover plates of the columns with variations in the cross sectional area, so that, in a direction parallel to its web, the distance between the outer faces of the cover plates of each successive column section upward is less than that of the preceding section. It also has been the practice with different loads due to different paneling or concentrations on upper floors and requiring different areas, to increase or decrease the dimensions over the outer faces of the column cover plates in accordance with the sectional area of the column. This practice has been due to the fact that in H-shaped columns as heretofore built, the web plates have been of uniform width and the distance back to back of the angles on the edges of the web plates a constant dimension, while the cross sectional areas of the columns differed and the distance between the outer faces of the cover plates of the columns varied in adjacent columns or in adjoining sections of a column or both.

With H-shaped columns built in the old way, in so far as I am aware, the girders connecting to columns have to be of different lengths for each variation in sectional area of columns. Also other difficulties are presented, especially in connection with wall columns. In the latter the successive sections of columns if centered over lower sections cause the connections for wall beams and girders at different floors, or at the same floor for similar columns having different areas, to vary on account of the wall beam or girder being a constant distance from face of walls and center of column. If the outer faces of columns for successive floors and adjacent columns are placed in a vertical plane to make the connections of the wall beams alike for adjacent columns and for successive floors, then the center of the columns become out of line for adjacent columns and for columns at successive floors, and this makes the interior framing to the columns different for each column, having a different area and different for each successive floor. Such arrangement also leads to complication in the location and setting of the columns due to the variations in column centers.

According to my invention a compound column is provided which has a uniform dimension over its flanges with varying cross sectional areas in different sections of the column. This construction also permits a column adjacent to the one shown but having a different area at each floor to be constructed with the same distance over the flanges. Thus the adjacent column may start with the section designated generally by the numeral 3 on same floor where column shown has section 2 and have section 4 on next floor, or same floor that column shown has section 3, and so on upward, both columns having the same distance over the outer faces of the flange angles.

In the accompanying drawings, forming part of this specification, Figure 1 is a side elevation showing the lengths or column sections of the upper portion of a compound column embodying my invention.

Figure 2 is a similar view showing the lengths or column sections of the lower portion of such column, being a continuation from the line X—X of Figure 1.

Figure 3 is a transverse section of the column on the line III—III of Figure 2.

Figure 4 is a transverse section on the line IV—IV of Figure 2.

Figure 5 is a transverse section of the column on the line V—V of Figure 1.

5 Figure 6 is a transverse section on the line VI—VI of Figure 1.

Figure 7 is a plan showing a typical building floor construction using compound columns made in accordance with my invention.

10 Figure 8 is a similar plan of a building floor at a higher elevation in the height of the building of Figure 7.

Referring now to Figures 1 and 2 of the drawings, the numeral 2 in a general way designates the lowermost length or section and 3 its lengthwise adjacent section, in a compound column made in accordance with my invention. The lower end of the 15 next section 4 rests on the upper end of the section 3 and the lower end of the upper section 5 rests on and is supported by the upper end of the adjoining section 4. The joints at the abutting ends of the transversely divided column sections 2, 3, 4 and 25 5 are joined by means of splice plates 6 in assembling the compound column.

By reference to Figures 3, 4, 5 and 6 of the drawings, it will be seen that each 30 length or transversely divided section of the compound column is formed of a web plate 7 having pairs of angles which are riveted to the sides of the web plates at the longitudinal edges thereof with the oppositely extending legs of the angles 8 forming flanges, to which, in the sections shown by Figures 3, 4, and 5, cover plates 10 are riveted.

The web plates 7 of the various sections 40 of the compound column generally are of the same thickness and likewise the angles 8 generally will be of the same size and cross sectional area, in each of the several lengths or sections making up the assembled 45 compound column. However, when found necessary or desirable the thickness of the web plates 7 and the size or thickness of the angles 8, or both size and thickness, may vary, in making the cross sectional area 50 of each column section less than that of the column section immediately below it.

Each of the column sections 2, 3 and 4 is provided with cover plates 10, these cover 55 plates as shown extending lengthwise from end to end of the section of which they form part. The cover plates are riveted to the angle members 8 of the column in the old and well understood manner. The cover plates 10 are made of varying thicknesses, each section or length of the compound column generally having cover plates 60 of less thickness than that of its lower, abutting section, but in columns embodying my invention the outer faces of the cover 65 plates on any one column section are in

alinement with the outer faces of the cover plates of its abutting column section or sections.

The uppermost section 5 of the column illustrated in the drawings is shown formed 70 of a web plate 7 and angles 8, the cover plates being omitted and the outer faces of the oppositely extending legs of the angles on the edges of the web plate 7 of this section of the column being in alinement with the outer faces of the cover plates 10 on the column section 4 immediately below it.

On account of the smaller load carried by the upper section of the compound columns, cover plates ordinarily will be unnecessary, but when found desirable the top section may have cover plates secured to the angles 8 in the same manner as in the lower sections of the column.

By reference to Figures 1 to 5 it will 80 be seen that the cover plates 10 on the section 2 of the columns are generally of greater thickness and of greater cross sectional area than those on the column section 3 supported by the section 2, shown 90 in Figure 3, and that the cover plates of the section 3 are of greater thickness than those on the section 4 of Figure 5. By reference to Figures 3 to 6 it also will be seen that the web plate 7 of each successive section upwardly of the compound column is of greater width than the web plate 7 of the section immediately beneath it and that the angles 8 of each successive column section upwardly are stepped outwardly from the angle members of the preceding column section.

Reference to Figures 7 and 8 will show 105 that although the cross sectional areas of the column sections illustrated in Figure 7 are greater than those of the column sections illustrated in Figure 8 the wall beams 11, 12 and 13 and 14, the floor girders 16 and the floor beams 15 of the floor of Figure 7 are of exactly the same length as 110 the corresponding members on the floor illustrated in Figure 8.

It also will be seen that the cover plates 10 on some of the column sections shown in Figure 7 are of greater thickness than 115 others in this Figure and that the same is true in regard to the columns shown in Figure 8 and, notwithstanding the differences in thickness of the cover plates and cross sectional area that the columns, in 120 a direction parallel to the webs thereof are of the same width, out to out of the cover plates, while the beams framed to these column sections are of the same length, not only on each floor but, when desired, may 125 be on each of the various floors of high buildings.

Obviously the columns of any one floor may be varied in cross section, to care for 130 differences in the loads on the columns, due

to different paneling, and concentrations on a higher floor, while the columns are all of the same overall dimension face to face of the cover plates.

5. It will be readily understood that by fabricating a column as above described the distance between the outer faces of the cover plates in a direction parallel to the side faces of the web plates is maintained the same throughout the entire length of the column, or throughout a series of stories, thereby eliminating the necessity of fillers at the splices, and providing a construction in which the floor girders and other parts connecting to the columns for the entire building or for any desired number of stories may be of the same length.

Another important advantage is that columns constructed in accordance with this invention will have the outer faces of the cover plates at a constant distance from the face of the walls, thus simplifying and facilitating the placing of brick, stone, terra cotta, or other material of which the walls are made. A further advantage of this column is that the overall dimensions of columns constructed in accordance with this invention will be the same on each floor and on successive groups of floors, which enables the forms for fireproofing to all be alike and facilitates the placing of fireproofing around columns.

While in Figures 1 to 6 a column is shown made up of four abutting lengths or sections, in which the distance face to face of the cover plates is the same in all of the column sections, it is not to be understood that in constructing buildings employing such columns that the columns need be of the same dimension face to face of the cover plates, in all sections of the column. For example, say in a building having twenty stories, it will be desirable to make the compound columns for the first ten stories of the same dimension face to face of the cover plates, and to make the columns for the next ten stories smaller, but in which the dimension face to face of its cover plates will be the same throughout the sections making up such column for the ten stories.

While I have described and illustrated only one specific construction of column embodying my invention, various other modified constructions may be made without departing from the scope of the appended claims.

I claim:—

1. A compound column comprising transversely divided column sections, said sections being arranged end to end in the erected column and each section having a web plate with angles on the edges of the web

plate and a cover plate secured to each edge of the web plate by said angles, the overall dimension of said column sections, in a plane parallel with the sides of said web plate, being the same in all sections and the thickness of the cover plates in some sections varying from that of other sections of the column.

2. A compound column comprising transversely divided column sections, said sections being arranged end to end in the erected column and each section having a web plate with angles on the edges of the web plate and a cover plate secured to each edge of the web plate by said angles, the overall dimension of said column sections, in a plane parallel with the sides of said web plate, being the same in all sections and the cross sectional area of the cover plates on at least one section varying from that of another section of the column.

3. A compound column comprising transversely divided column sections, said sections being arranged end to end in the erected column and each section having a web plate with angles on the edges of said web plate and at least one cover plate secured to each edge of the web plate by said angles, the overall dimension of said column sections in a plane parallel with the sides of said web plate being the same in all of said sections and the cross sectional area of at least one section varying from that of another section of the column.

4. A compound column comprising transversely divided column sections arranged end to end in the erected column, each section having a web plate, angles on the edges of said web plate and a cover plate secured to each edge of the web plate by said angles, the overall dimensions of said sections, in a plane parallel with the sides of said web plate, being the same in all of said sections, and the cross sectional area of the sections decreasing from the lowermost section upward.

5. A compound column comprising transversely divided column sections arranged end to end in the erected column, each section having a web plate, angles on the edges of said web plate and a cover plate secured to each edge of the web plate by said angles, the overall dimension of said sections, in a plane parallel with the sides of said web plates, being the same in all of said sections and the thickness of the cover plates decreasing from the lowermost section upward.

In testimony whereof, I have hereunto signed my name.

FRANCIS LEE CASTLEMAN.
